(57) **CLAIM**

I claim the ornamental design for a grille assembly for a bathroom ventilation fan, as shown and described.

DESCRIPTION

FIG. 1 is a first perspective view of a grille assembly for a bathroom ventilation fan of the invention;

FIG. 2 is a second perspective view of the grille assembly of FIG. 1;

FIG. 3 is a top view of the grille assembly of FIG. 1;

FIG. 4 is a bottom view of the grille assembly of FIG. 1;

FIG. 5 is a first side view of the grille assembly of FIG. 1;

FIG. 6 is a second side view of the grille assembly of FIG. 1;

FIG. 7 is a first sectional view of the grille assembly of FIG. 1, taken along section line 7-7 of FIG. 3;

FIG. 8 is a second sectional view of the grille assembly of FIG. 1, taken along section line 8-8 of FIG. 3;

FIG. 9 is a perspective view of a second embodiment of a grille assembly for a bathroom ventilation fan of the invention;

FIG. 10 is a second perspective view of the grille assembly of FIG. 9;

FIG. 11 is a top view of the grille assembly of FIG. 9;

FIG. 12 is a bottom view of the grille assembly of FIG. 9;

FIG. 13 is a left side view of the grille assembly of FIG. 9;

FIG. 14 is a right side view of the grille assembly of FIG. 9;

FIG. 15 is a first sectional view of the grille assembly of FIG. 9, taken along section line 15-15 of FIG. 11;

FIG. 16 is a second sectional view of the grille assembly of FIG. 9, taken along section line 16-16 of FIG. 11;

FIG. 17 is a perspective view of a third embodiment of a grille assembly for a bathroom ventilation fan of the invention;

FIG. 18 is a second perspective view of the grille assembly of FIG. 17;

FIG. 19 is a top view of the grille assembly of FIG. 17;

FIG. 20 is a bottom view of the grille assembly of FIG. 17;

FIG. 21 is a left side view of the grille assembly of FIG. 17;

FIG. 22 is a right side view of the grille assembly of FIG. 17;

FIG. 23 is a first sectional view of the grille assembly of FIG. 17, taken along section line 23-23 of FIG. 19; and,

(Continued)

FIG. 24 is a second sectional view of the grille assembly of FIG. 17, taken along section line 24-24 of FIG. 19. The dashed broken lines illustrate portions of the grille assembly for a bathroom ventilation fan that form no part of the claimed design.
